(57) **CLAIM**

The ornamental design for the handle of surgical instrument, as shown and described.

DESCRIPTION

FIG. 1 is a front, top and right side perspective view of a handle of surgical instrument, showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is a cross section view thereof; taken along the line 8-8 in FIG. 4, showing only the housing structure.

The broken lines, shown in the FIG. 1-7 views, immediately adjacent the claimed areas represent the bounds of the claimed design while all other broken lines are directed to environment and are for illustrative purposes only. To illustrate the exterior peripheral shape of the article in cross section, the broken lines shown in FIG. 8 are for the purpose of illustrating unclaimed portions of the handle of surgical instrument. The broken lines form no part of the claimed design.
